UNITED STATES PATENT OFFICE.

JOSHUA P. EATON, OF WOBURN, MASSACHUSETTS.

DESIGN FOR A CRIMPING-FORM.

SPECIFICATION forming part of Design No. 21,163, dated November 10, 1891.

Application filed July 28, 1891. Serial No. 401,011. Term of patent 14 years.

To all whom it may concern:

- Be it known that I, JOSHUA P. EATON, a citizen of the United States, residing at Woburn, county of Middlesex, State of Massachusetts, 5 have invented and produced a new and original Design for Crimping-Forms, of which the following is a specification, reference being had to the accompanying drawings, forming part thereof.
- 10 Figure 1 is a sectional view of the crimping-form embodying this invention; Fig. 2, a cross-section of the same, taken on the dotted line $x\ x$; Fig. 3, a cross-section of the same, taken on the dotted line $y\ y$; and Fig. 4, a rear 15 end view of the crimping-form shown in Fig. 1.
- The general contour of the crimping-form as represented in Fig. 1 comprehends a toe, instep, shank, heel, and top portion.
- 10 The form is chamfered on each side from the 20 lines 1 2 in a direction toward the rear or heel edge 4 and also from the lines 1 3 in a direc-

tion toward the front edge 5, leaving a thickened and substantially flat portion 6, said portion having parallel flat sides, as best seen in Fig. 3. The heel-edge 4 and the front edge 25 5 are sharpened or tapered.

I claim—

The design for a crimping-form herein shown and described, the same comprising a block having its general contour such as to 30 comprehend a toe, instep, shank, heel, and top portion and having a substantially thick portion 6, with parallel flat sides and a sharpened front and rear edge 5 4, the block tapering thereto from said thick portion, as set forth. 35

In testimony whereof I have signed my name to this specification in the presence of two subscribing witnesses.

JOSHUA P. EATON.
